UNITED STATES PATENT OFFICE

ARTHUR F. STUBENBERG, OF WAHIAWA, TERRITORY OF HAWAII

SUBSOILER

Application filed October 27, 1927. Serial No. 229,000.

This invention pertains to plowing or furrowing devices, and more particularly to that type of devices to be used in subsoiling.

On plantations or farms of various kinds, it is often desirable or necessary to subsoil during the growth of various crops. For instance, on sugar and pineapple plantations, it is very necessary that subsoiling be effected between the various rows of the crop at different periods of their growth. Heretofore it has been necessary to employ a single subsoiler drawn by mules and worked by two men, for performing this operation, which of course, it will be appreciated, is more or less ineffective as well as costly, as not only is it slow but a single subsoiling operation is not effective as a sufficient depth is oftentimes not reached. With the machines in use, subsoiling points are attached to the machine and the machine is pulled either by tractor power or by mules, which is also unsatisfactory as such a machine itself cannot be heavy enough for the points to penetrate a sufficient distance, and then too, the machine cannot be accurately guided unless another man is employed, so that here again the cost of operation of such a machine on a large plantation is exorbitant.

It is therefore an object of this invention to provide an inexpensive attachment for subsoiling which will increase the amount of work accomplished at a material saving in cost.

Another object is to provide a device which is more efficient, performs its function more evenly, and is readily adjustable to different degrees of operation.

Still another object is to provide a machine capable of more extensive operation and one which may be easily controlled at a single point by a single person.

A further object is to provide controls for the operating means of a subsoiler which are positive, are of small number and so disposed as to be capable of operation from a single source.

With these and various other objects in view, the invention consists of certain novel features of construction and operation as

will be more fully described and particularly pointed out in the specification, drawings, and claims appended hereto.

In the drawings, wherein like reference characters are used to designate like parts—

Figure 1 is a side elevation of the subsoiling device as applied to a tractor, the tractor being indicated generally in dotted lines;

Figure 2 is an end elevation of the device shown in Figure 1, showing the points in subsoiling operation; and

Figure 3 is a fragmentary end elevation of the bracket attachment between the yoke and the tractor frame, the same being taken substantially in the plane as indicated by the line 3—3 of Figure 1.

It will of course be appreciated that though this device is described as applied to a tractor that it may just as readily be applied to any other vehicle capable of this use, and while subsoiling points are particularly referred to, it will be understood that these points may include disc or mold board plows or harrows, etc., as well as specific subsoiling points.

Tractor 10 is provided on either side thereof with a frame 11 to which may be attached at any convenient point a bracket assembly 12. Said assembly consists essentially of a pair of bracket plates 13 and 14 provided with adjustable pin holes 15, said bracket being braced to the tractor by means of fore and aft braces 16 and transverse braces 17. An arm 18 is pivoted to the bracket assembly by means of the bolts 19 disposed in any of the selected pin holes 15. The other end of the arm 18 is bracketed or secured by means of the connecting plates or brackets 20 and 21 to the upper and lower subsoiling arms 22 and 23 which may conveniently be in the form of yokes. Said yokes are secured together at their central portions and embrace opposite sides of the arm 18. The arms are provided with bolt holes 25 adapted to provide adjustable securing means for the subsoiling points 26 fastened to said yokes by means of clamps 27 and bolts 28.

In the present disclosure the subsoiling

arms 22 and 23 are constructed in the form of a yoke for the purpose of arching the central portions thereof upwardly out of the path of the growing crops. The machine, as shown, arches the rows of crops and presents 5 the subsoiling points for work in the aisles between the rows; the arched construction of the yokes provides clearance, eliminating danger of contact and damage to the crops by the yoke.

10 As already explained, the subsoiler arms are in the form of yokes, the same being bent upwardly at the center thereof and so disposed as to have contacting relation with each other, though it will be appreciated 15 that should the subsoiler arms be adapted only for plow or harrow use, the same may be substantially straight across and properly provided with the disc or harrow points 20 along the length of the arms. For manipulation of said yokes, a frame lift or hoist 29 is provided which consists essentially of upright members 30 secured to the tractor body, and a transverse member 31 bracketed to the 25 upright members by means of brackets 32.

30 A jack shaft 33 is driven from the motor or engine through gear box 34, the end of said shaft being suitably mounted in bearings 35 supported by the bracket assembly 36. Said jack shaft carries a windlass or 35 drum 37 loosely mounted thereon for rotary movement and conveniently disposed with reference to the hoist frame 29. Between one end of the drum 37 and the jack shaft, there is disposed any suitable clutch means 38 for the purpose of selectively establishing connection between said shaft and said drum. A pawl and ratchet 39 and 40 are provided at the other end of said drum normally in engagement for preventing the 40 drum from revolving. The pawl is operated by means of a release pedal 41 conveniently disposed with respect to the driver's seat 42, said pedal being pivoted to the tractor at 43 45 and connected to the pawl by means of a link 44. A clutch lever 45 pivoted to the frame at anchor plate 46 is provided with a thrust collar 47 preferably encircling the jack shaft and adapted to move the clutch 50 elements through engagement with a proper clutch collar (not numbered), said lever being connected to a clutch lever handle 48 suitably pivoted at 49 for operation from the driver's seat 42, said lever 48 being connected to the clutch lever by means of the link 50. The clutch lever handle is connected by means of an adjustable link 51 to one arm of a bellcrank or automatic release arm 52, said release arm being pivoted 55 to the uprights at 53 and having a contractile spring 54 connected to said uprights and to the other arm of the release arm so that the action of the spring will normally cause disengagement between the clutch elements and the drum.

60 The tractor is provided with a guard 55 so disposed with reference to the yokes as to prevent said yokes from interfering with proper operation of the tractor or the devices disposed thereon. A block and tackle 56 is disposed between the yokes and the upper frame member 31 of the hoist frame 29, the sheaves 57 and 58 being releasably connected to the yokes and frame member 31 by means of links 59 and 60. The rope of the block and tackle assembly runs from the upper sheave block through guide rollers 61 down to and around the drum 37 in such a manner that the pawl and ratchet 39 and 40 normally prevent rotation of said drum. Holding means 62 are provided on either side of the uprights 30 and are of suitable length and provided with hooks 63 for the purpose of engagement with the yokes to hold the same in raised position, forming a further supporting means for said yokes to thereby relieve the tackle of the strain caused by the weight of the yokes and points.

65 In the operation of the device, it will be seen that it is only necessary to properly adjust the subsoil elements 26 with respect to the yokes 22 and 23, positioning them so that they will properly function to subsoil the rows of crop. After the device has performed its function and when it is desired to raise the yoke to a position to render the subsoil elements inoperative, it is only necessary to move the clutch handle 48 in a counter-clockwise direction as viewed in Figure 1, causing the thrust collar 47 to engage with the clutch collar to establish connection between the jack shaft 33 and the drum 37. Drum 37 will then rotate with the shaft and tackle to raise the yokes to a position where the subsoil elements will be inoperative, the yokes pivoting around the point 19 on the frame 11. When the yokes have been raised to the desired height, the handle 48 may be released and the spring 54 will render the clutch inoperative with respect to the drum, the pawl and ratchet 39 and 40 maintaining the drum in fixed position, locking the yokes in a raised position where it will be understood the hooks 63 may then be attached to the yokes, forming a further support for the same. When it is desired to lower the yokes, it will of course be appreciated that the clutch may be engaged partially to form a brake, but this is not necessary. It is only necessary that the hooks 63 be disengaged and the pawl and ratchet be disengaged to thereby allow the elements to move under their own weight to operative position, though it is appreciated of course that a double acting clutch may be provided to positively move the yokes to lowered position by means of the tractor motor.

70 75 80 85 90 95 100 105 110 115 120 125 130
It will of course be understood that I do not wish to be limited by the exact embodiment.

ment of the device shown as other and various embodiments will of course occur to those skilled in the art.

I claim:

- 5 1. In a device of the character described the combination of a vehicle, a frame pivotally attached to said vehicle at substantially the mid-point of its length, said frame comprising a pair of side arms and a cross arm connecting the ends of said side arms, said cross arm being located in close proximity to the end of said vehicle and means mounted at the end of said vehicle and connected to said frame for raising and 10 lowering said frame, said cross arm being arched throughout its central portion.
- 15 2. In a device of the character described, the combination of a vehicle, power means for driving said vehicle, winding means carried by said vehicle, and means for connecting and disconnecting said winding means for operation by said power means, a U-shaped frame surrounding and enclosing the rear end of said vehicle, having its 20 base portion in close proximity to the rear end of said vehicle and the ends of its arms pivoted to opposite sides of the intermediate portion of the length of said vehicle, an up-standing bracket mounted on the rear end 25 of said vehicle and having line engaging means at its top, and a line connecting the base of said U-shaped frame and winding means, and passing over said line engaging means.
- 30 35 Signed at Honolulu, T. H., this 10th day of October, 1927.
ARTHUR F. STUBENBERG.
